Bell Telephone Laboratories, Incorporated, New
York, N. Y., a corporation of New York

Application December 9, 1947, Serial No. 143,066

Term of patent 14 years

(Cl. D26—14)

To all whom it may concern:

Be it known that I, George R. Lum, a citizen of the United States, residing at South Wilton, in the county of Fairfield and State of Connecticut, have invented a new, original, and ornamental Design for a Wall Mounting for a Hand Telephone, of which the following is a specification, reference being had to the accompanying drawing, forming a part thereof.

Fig. 1 is a perspective elevational view of a wall mounting for a hand telephone, showing my new design and

Fig. 2 is a side view of the mounting.

I claim:

The ornamental design for a wall mounting for a hand telephone, as shown.

GEORGE R. LUM.
